OR 012-059

EX

No. 12,059

DECEMBER 7, 1880

UNITED STATES PATENT OFFICE.

GEORGE S. BARKENTIN, OF NEW BRITAIN, CONNECTICUT, ASSIGNOR TO
P. & F. CORBIN, OF SAME PLACE.

DESIGN FOR A KEY-BOW.

SPECIFICATION forming part of Design No. 12,059, dated December 7, 1880.

Application filed September 24, 1880. Term of patent 7 years.

To all whom it may concern:

Be it known that I, GEORGE S. BARKENTIN, of New Britain, in the county of Hartford and State of Connecticut, have invented and produced a new and original Design for a Key-Bow, of which the following is a specification, reference being had to the accompanying wood engraving, forming part thereof.

The leading feature of my design consists in the peculiar shape of the bow, springing from a central rosette at the end of the key-shank.

A is the bow, which is made oval in the contour of its upper surface. The lower surface is also oval, but somewhat flattened, and is

made to spring from a central rosette, B, on 15 the end of the key-shank. The rosette B consists of eight sunken petals springing from a circle in the center and surrounded by a sunken circular line.

I claim—

The design for a key-bow herein shown and described, the same consisting of the ear-shaped bow A, springing from a central rosette, B, at the end of the key-shank.

GEORGE SLATER BARKENTIN.
